United States Patent Office

Des. 187,783
Patented May 3, 1960

187,783

GARDEN SHELTER

Leonard Summers, Richmond; Surrey, England, assignor to Monsanto Chemical Company, St. Louis, Mo., a corporation of Delaware

Application December 21, 1959, Serial No. 58,747

Term of patent 14 years

(Cl. D13—1)

FIG. 1

FIG. 2

FIG. 3

Figure 1 is a perspective view of a garden shelter embodying my new design.

Figure 4 is a top plan view thereof.

I claim:

The ornamental design for a garden shelter, substantially as shown.
